[57] CLAIM

The ornamental design for a soap dish fixture, as shown and described.

DESCRIPTION

FIG. 1 is a perspective view of a wall-mounted soap dish fixture, showing our new design;

FIG. 2 is a top plan view thereof;

FIG. 3 is a side elevational view thereof taken from the left of FIG. 2; and

FIG. 4 is a front elevational view thereof.

The shading in the views is intended to represent a metallic reflective surface at the wall mounting end of the fixture as contrasted with the transparent surface for the remainder of the fixture.
